UNITED STATES PATENT OFFICE.

GEORGE W. FOWLE AND FRED F. FELDMANN, OF SAN JOSE, CALIFORNIA.

EXHAUST BOX.

Application filed September 7, 1922. Serial No. 586,753.

To all whom it may concern:

Be it known that we, GEORGE W. FOWLE and FRED F. FELDMANN, citizens of the United States, and residents of San Jose, in the county of Santa Clara and State of California, have invented certain new and useful Improvements in Exhaust Boxes, of which the following is a specification.

This invention relates particularly to that type of exhaust box used in the canning of fruits where the temperature of the contents of the can must be raised to a certain point before the cover is applied thereto.

It is the object of our invention to provide a device of the character indicated that will receive the cans, move them lengthwise thereof at fixed intervals, and discharge them without subjecting them to such sudden movements as to spill any of the liquid contents therefrom.

It is a further object of our invention to provide a means whereby a plurality of can supporting shelves may be revolved about a given axis, the rotating means including means for positively maintaining the shelves in their normal horizontal positions, and permitting high sides to the shelves.

It is a still further object of our invention to provide a device of the character indicated that will be simple in construction, economical to manufacture, positive in operation, and highly efficient in its practical application.

In the drawings:—

Figure 1 is a transverse cross-section taken through our improved exhaust box on line 1—1 of Figure 2.

Figure 2 is a sectional plan view of the same taken on line 2—2 of Figure 1.

Figure 3 is an enlarged detail of the supporting means for the can carrying shelves, parts being broken away.

Figure 4 is a reduced elevation of the eccentrically mounted plates.

Referring more particularly to the drawings we show at 1—1 annular end members supported upon legs 2—2 and having bearings 3—3 formed therein and located eccentrically with relation to the center thereof. In each end member 1 is formed a pocket 4 enclosing a pinion 7 mounted on shaft 6 which is mounted in bearings 5 in member 1 and driven by a power mechanism not shown by driving pulley 8.

The end members 1 are spaced from each other by a sheet metal cover or drum which surrounds the same and is secured thereto by any suitable means such as bolts or rivets, the whole forming an annular box or drum 60 having an opening in the top thereof as at 10 which is covered by a plate 11 held in place by strips 12. The said opening 10 extends the full length of the drum for purposes hereinafter disclosed. 65

Formed integrally with ends 1 and upon their inner surfaces and with their centers coinciding with the center of said ends are bearings 13 which are thus placed eccentric with relation to the shaft bearings 3 as 70 shown clearly in Figure 4.

Revolutely mounted upon bearings 13 are annular plates 14 having equally spaced orifices 15 formed therein near the periphery thereof as shown. Mounted so as to revolve freely in each of the orifices 15 is a crank element 16, the outer portion of which is bent outwardly at right angles to the ends in orifices 15 as at 17 the distance between the centers of the two ends being 75 80 equal to the distance from the center of shaft bearings 3 to the center of plate bearings 13. The outer ends of portions 17 are squared as at 18.

Spaced a distance from plates 14 so as to allow connecting cranks 16 to pass therebetween are large gears 19 mounted upon shaft 20 passing through bearings 3 in end plates 1, the gears 19 meshing with pinions 7. Spaced equally around gears 19 are a 85 90 series of orifices 21 corresponding in number to the connecting cranks 16 and through which the end portions 17 of the same pass. We now have a large annular drum having revolving plates 14 connected to driven gears 19 by connecting cranks 16, the two driven gears 19 being rotated at a uniform speed by means of driving pulley 8, shaft 6 and pinions 7 as shown.

Extending longitudinally between gears 19 are a series of can carrying shelves 22 supported upon the squared ends 18 of connecting links 16 by means of bearing portions 23 slotted at 24 to take the said squared ends as shown, the shelves 22 having a smooth bottom 25 and upstanding flanges on either side thereof as at 26. 100 105

The ends 18 of connecting cranks 16 being squared and the slots 24 conforming thereto to the bottom 25 and upstanding flanges 26 110

are always held in a horizontal position and the cans carried thereby in a vertical plane. Now as the gears 19 revolve the shelves are carried in a circular path by the same, but due to the form, proportions and connections between the shelves, the gears and the plates 14 by connecting cranks 16, the shelves are maintained in their normal horizontal plane during the entire revolution because of the fact that the disc 14 is eccentrically placed with relation to gears 19 as is clearly shown.

End members 1 are cut away at the upper edge thereof as at 27 to allow discs 28 to project inwardly thereof, said discs 28 being so placed as to just clear gears 19 and have their upper edge on a plane with the bottoms 25 of shelves 22 as shown.

The discs 28 are revolvably mounted in bearings 29 and 30 by means of shaft 31, the same being driven in the direction indicated by the arrows by means of gears 32-33 mounted as shown.

Mounted upon the inner edge of end members 1 as shown and extending along the upper edge of disc 28 is a can guide 34 which is placed at the can entering end of the exhaust box only.

Mounted upon and depending from the cover 11 are a series of can moving plates 35, the same being so placed and proportioned as to take a can which is on the shelf ascending to the extreme upper position and move the same over the space of one can as the shelf moves from that position to its highest point or its upper position as shown. This action thus moves a can over one space all along the upper shelf which thus makes a space for a can coming from the feeding disc 28 and places a can upon the discharge disc as shown. Thus every time a shelf reaches the top of its path of travel we feed in a can and discharge another can which has been moved successively and slowly from one end of the machine to the other.

During this slow travel through the machine the contents of the cans are heated by means of hot air or steam supplied through the heating pipes 36 lying along the bottom of the drum as shown.

The degree of heat to which the different fruits or different sized cans of fruit is subjected is regulated by the speed with which the shelves are rotated which, of course, governs the length of time it takes a can to pass through the machine.

It is apparent that for different sized cans different shelves 22 and different can moving members 35 will have to be used due to the difference in diameter and height of different capacity cans such as pints, quarts, gallons, etc.

We have provided novel means for this contingency which is easily and quickly put

into effect. By removing cover plate 11 we can raise the shelves from their supporting means 18 as the drum is revolved and place other shelves of greater or less width in place thereof as the size of the cans demand. As the can moving members 35 are secured to the cover 11 we replace the cover removed by another having the proper number and size of can moving elements thereon and the machine is again ready for use.

It is readily apparent that we have invented an improved exhaust box which will easily and quickly handle a large amount of canned fruit of all sizes with a minimum amount of labor and power expended by means of a machine which is simple of construction, easily manufactured and one that is highly efficient in its practical application.

It is to be understood, of course, that while we have herein shown and described one particular embodiment of our invention, that changes in form, construction, proportions and method of operation may be made within the scope of the appended claims.

We claim:

1. A device of the character indicated comprising a supporting frame, a plate revolvably mounted thereon, a second plate revolvably mounted in parallel and eccentric relation to said first plate, a plurality of annularly arranged cranks revolvably mounted in and connecting said plates, and driving means connected to one of said plates.

2. A device of the character indicated comprising a supporting frame, a plate revolvably mounted thereon, a second plate revolvably mounted in parallel and eccentric relation to said first plate, a plurality of annularly arranged cranks revolvably mounted in and connecting said plates, and driving means connected to one of said plates, the shanks of each crank being equal in length to the distance between the centers of the two plates.

3. A device of the character indicated, comprising a supporting frame, spaced parallel and axially aligned plates revolvably mounted thereon, a second plate revolvably mounted in parallel and eccentric relation to each of said first plates and within the same, a plurality of annularly arranged cranks revolvably mounted in and connecting each pair of plates, and extending within each inner plate, and a shelf mounted upon each opposing pair of cranks.

4. A device of the character indicated comprising a revoluble carrier element, a second element revolvably mounted in parallel and eccentric relation thereto, and a plurality of annularly arranged cranks revolvably mounted in and connecting said elements.

5. A device of the character indicated

- comprising a pair of spaced revoluble carrier elements, a second element revolvably mounted in parallel and eccentric relation to each carrier element, a plurality of annularly arranged cranks revolvably mounted in and connecting said elements near the peripheries thereof and extending through said carrier elements, and a can shelf mounted upon each opposing pair of cranks.
6. A structure comprising spaced rotatable members, means carried thereby for supporting shelves therebetween, and means for maintaining the first means in position for supporting the shelves horizontally throughout the rotary movement of said members.
7. A structure comprising spaced rotatable members, means carried by each member for supporting the adjacent end of a shelf interposed therebetween, and means rotatable with said members eccentrically thereto for varying the relation between said members and said first means to support the shelf horizontally throughout the rotary movement of said members.
8. A structure comprising spaced rotatable driven members, means journaled in each for supporting an article therebetween, and a second rotatable member associated with each first rotatable member and arranged on the outer side thereof, said means having offset journaled portions in said second rotatable member and the latter being journaled eccentric to the first members.
- 30 9. A structure comprising a pair of rotatable members journaled eccentrically relative to each other, and a support having offset journal bearings in said members.
- 40 10. A structure comprising a pair of rotatable members journaled eccentrically relative to each other, and a crank shape member having offset journal bearings in said rotatable members and projecting at one end through the adjacent rotatable member to constitute a support.
- 45 11. A structure comprising a casing, spaced rotatable members journaled therein, a series of supports projecting inwardly from each member and journaled therein, a plurality of shelves supported at opposite ends by said supports, and means for holding said supports to maintain the shelves horizontally disposed throughout rotary movement of said rotatable members.
- 50 12. A structure comprising a casing, spaced rotatable members journaled therein, a series of supports projecting inwardly from each member and journaled therein, a plurality of shelves supported at opposite ends by said supports, a second rotatable member associated with each first member and journaled eccentric thereto, the offset portions being journaled in said second rotatable members, and means for driving one of said rotatable members.
- 55 13. A structure comprising a casing, spaced rotatable members journaled therein, a series of supports projecting inwardly from each member and journaled therein, a plurality of channeled shelves supported at opposite ends by said supports, a second rotatable member associated with each first member and journaled eccentric thereto, means connecting the supports to the adjacent second rotatable member for maintaining the shelves in horizontal position during movement of said rotatable members, and means for advancing articles placed on the shelves along the same.
- 60 14. A structure comprising a casing, spaced rotatable members journaled therein, a series of supports projecting inwardly from each member and journaled therein, a plurality of channeled shelves supported at opposite ends by said supports, a second rotatable member associated with each first member and journaled eccentric thereto, means connecting the supports to the adjacent second rotatable member for maintaining the shelves in horizontal position during movement of said rotatable members, means for feeding cans to one end of the shelves, and means arranged within the casing in the path of the cans for advancing the same along the shelves.
- 65 15. A structure comprising a casing, having a removable cover, a movable support within the casing designed to support articles and have them advanced thereover, and means carried by the removable cover for advancing the articles on the support by and during movement thereof.
- 70 16. A structure comprising a casing, having a removable cover, a movable support within the casing designed to support articles and have them advanced thereover, and means carried by the removable cover for advancing the articles on the support by and during movement thereof.
- 75 17. A structure comprising a casing, having a removable cover, a movable support within the casing designed to support articles and have them advanced thereover, and means carried by the removable cover for advancing the articles on the support by and during movement thereof.
- 80 18. A structure comprising a casing, having a removable cover, a movable support within the casing designed to support articles and have them advanced thereover, and means carried by the removable cover for advancing the articles on the support by and during movement thereof.
- 85 19. A structure comprising a casing, having a removable cover, a movable support within the casing designed to support articles and have them advanced thereover, and means carried by the removable cover for advancing the articles on the support by and during movement thereof.
- 90 20. A structure comprising a casing, having a removable cover, a movable support within the casing designed to support articles and have them advanced thereover, and means carried by the removable cover for advancing the articles on the support by and during movement thereof.
- 95 21. A structure comprising a casing, having a removable cover, a movable support within the casing designed to support articles and have them advanced thereover, and means carried by the removable cover for advancing the articles on the support by and during movement thereof.
